SCREEN GRID RELAY CIRCUITS

Werner Buschbeck, Berlin, Germany, assignor to
 Telefunken Gesellschaft für Drahtlose Tele-
 graphie m. b. H., Berlin, Germany, a corpora-
 tion of Germany

Application January 25, 1933, Serial No. 653,419
 In Germany February 29, 1932

4 Claims. (Cl. 179—171)

This invention relates to neutralizing circuits for screen grid tubes.

In order to secure a sufficient freedom from reaction in screen grid tubes, it is necessary that the screen grid actually carries cathode potential. This requirement can no longer be easily complied with in particular in the case of short waves and high anode potentials, since the current J_s , passing across the anode screen grid capacity, causes a voltage drop in the lead, which always requires a certain length, connecting the screen grid with the cathode, or in the screen grid block condenser respectively. This voltage drop may only be kept small by decreasing the current flowing through this lead which, in accordance with the present invention, may be obtained by a bridge circuit in which the screen grid connection and the cathode point K become points of equal potentials. To this end it is simply necessary to choose the neutralizing capacity of the screen grid in such a manner so as to fulfill the equation

$$\frac{C_{NS}}{C_{SA}} = \frac{C_2}{C_1}$$

The novel features of the invention have been pointed out with particularity in the claims appended hereto.

The nature of the invention and the manner in which the invention may be carried out will be described more in detail hereinafter.

In describing the invention reference will be made to the drawing, throughout which like reference characters indicate like parts, and in which:

Figure 1 serves to illustrate the novel features of this invention; while,

Figures 2, 3 and 4 show relay circuits including screen grid repeaters arranged in accordance with the present invention.

Referring to Figure 1, 2 indicates an inductance connected between the control grid 4 and cathode 6 of a screen grid tube 8. The inductance 2 may be coupled to any source of ultra high frequency oscillations to be relayed and/or amplified.

10 indicates a tuned circuit coupled between the anode 12 and cathode 6 of tube 8 by way of a potential source 14. The circuit 10 may be tuned to the fundamental frequency or to a harmonic thereof. The screen grid electrode 16 may be charged by way of an inductance 18 from the source 14. In short wave work it is desirable that the screen grid electrode 16 be maintained at ground potential with respect to the alternating current potentials. This is accomplished

by connecting the screening grid electrode directly to the cathode by way of a by pass condenser B_s , as shown. The connecting leads, even under the best of conditions, must have some length and therefore there is a voltage drop caused by the current J_s flowing in the connecting leads. Also, the capacity B_s offers some impedance to the alternating currents J_s causing a further potential drop between the screen grid electrode and the cathode. This potential drop may only be kept small by reducing or decreasing the current flow in the screen grid lead including the capacity B_s . A reduction in the flow of current in this lead may be accomplished by the utilization of a bridge circuit, as disclosed in Figure 2.

In Figure 2 the screen grid electrode 16 is connected directly to a point S at one corner of a bridge circuit, the other corner K of which is connected to the cathode. The capacity between the anode 12 and screen grid electrode 16, indicated by the dotted condenser C_{SA} connected between the points A and S, forms one arm of the bridge, another arm of which is formed by a capacity C_1 which may include the capacity between the anode and cathode 6, and a third arm of which includes a capacity C_2 . The screen grid neutralizing capacity C_{NS} is now chosen in such a manner to fulfill the equation

$$\frac{C_{NS}}{C_{SA}} = \frac{C_2}{C_1}$$

In this circuit the points S and K are at the same potential with respect to alternating currents, but the point K is at cathode potential. Therefore, there is no current flowing between the screen grid 16 and cathode 6.

In Figure 3 the screen grid electrode 16 is also connected in a balanced bridge circuit in such a manner that there is no potential drop with respect to the alternating currents relayed in the tube 8 between the screen grid and the cathode. Here the anode to control grid electrode capacity is shown by dotted lines at CAG.

This bridge circuit does not render the arrangement more complicated as may at first be expected, since for short waves the remaining amount of grid-anode capacity must in the most cases be neutralized despite the presence of the screen grid for which purpose a bridge circuit is required at any case (Figure 3).

Moreover, in the case of the pushpull arrangements of screen grid tubes, the screen grid capacity of the pushpull tube can be used at the

same time as neutralizing capacity for the screen grid (Figure 4).

Having thus described my invention and the operation thereof, what I claim is:

- 5 1. In combination with a screen grid amplifier, a source of ultra high frequency currents coupled between the control grid and cathode, an output circuit connected to the anode of the amplifier, a source of positive screen grid potential connected between the screen grid and cathode, a radio frequency condenser connected between the screen grid and cathode in shunt with said potential source, and a capacity bridge connected in said output circuit, said screen grid and cathode being connected to conjugate points on the bridge. 80
- 10 2. In combination with a screen grid amplifier, a source of ultra high frequency currents coupled between the control grid and cathode, an output circuit connected to the anode of the amplifier, a source of positive screen grid potential connected between the screen grid and cathode, a radio frequency condenser connected between the screen grid and cathode in shunt with said potential source, and a capacity bridge connected in said output circuit, said screen grid and cathode being connected to conjugate points on the bridge. 85
- 15 3. In combination with a screen grid amplifier, a source of ultra high frequency currents coupled between the control grid and cathode, an output circuit connected to the anode of the amplifier, a source of positive screen grid potential connected between the screen grid and cathode, a radio frequency condenser connected between the screen grid and cathode in shunt with said potential source, and a capacity bridge connected in said output circuit, said screen grid and cathode being connected to conjugate points on the bridge, and one arm of said bridge comprising the screen grid-anode capacity of said amplifier. 90
- 20 4. In combination with a screen grid amplifier, a source of ultra high frequency currents coupled between the control grid and cathode, an output circuit connected to the anode of the amplifier, a source of positive screen grid potential connected between the screen grid and cathode, a radio frequency condenser connected between the screen grid and cathode in shunt with said potential source, and a capacity bridge connected in said output circuit, said screen grid and cathode being connected to conjugate points on the bridge, and an additional screen grid amplifier connected between said ultra high frequency current source and said output circuit in push pull relation to said first screen grid amplifier, said bridge being connected between the screen grid and cathode of said second amplifier tube. 95
- 25 5. In combination with a screen grid amplifier, a source of ultra high frequency currents coupled between the control grid and cathode, an output circuit connected to the anode of the amplifier, a source of positive screen grid potential connected between the screen grid and cathode, a radio frequency condenser connected between the screen grid and cathode in shunt with said potential source, and a capacity bridge connected in said output circuit, said screen grid and cathode being connected to conjugate points on the bridge, and said shunt condenser being connected between said conjugate points. 100
- 30 6. In combination with a screen grid amplifier, a source of ultra high frequency currents coupled between the control grid and cathode, an output circuit connected to the anode of the amplifier, a source of positive screen grid potential connected between the screen grid and cathode, a radio frequency condenser connected between the screen grid and cathode in shunt with said potential source, and a capacity bridge connected in said output circuit, said screen grid and cathode being connected to conjugate points on the bridge, and said shunt condenser being connected between said conjugate points. 105
